UNITED STATES PATENT OFFICE.

HOWARD H. HUMMEL, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

ACCUMULATOR-CONTROL MECHANISM.

Application filed May 28, 1923. Serial No. 642,092.

To all whom it may concern:

Be it known that I, HOWARD H. HUMMEL, a citizen of the United States, and a resident of Bethlehem, Lehigh County, State of Pennsylvania, have invented certain new and useful Improvements in Accumulator-Control Mechanism, of which the following is a specification.

This invention relates to improvements in mechanism for controlling the flow of fluids particularly under high pressure, and is especially adapted for use with accumulators in connection with an hydraulic power system.

The object of the invention is to provide mechanism that will prevent water hammering in the pipes incident to the abrupt stoppage of the accumulator in any position of its stroke, and eliminate excessive pressures thus occasioned; another object of the invention is to provide automatic means which will function to choke or restrict the flow from the accumulator when an abnormal amount of fluid is suddenly required; a further object of the invention is to provide a device which is self acting and will automatically choke the accumulator to effectively prevent egress of water therefrom when a break occurs in the pressure line; a still further object is to provide mechanism operated by the pressure of the fluid for automatically restricting flow of fluid from the accumulator; moreover, the invention provides a cushioning means for the accumulator in combination with an automatic choking device whereby the latter will act effectively without being subjected to undue stress.

The accompanying drawings forming a part of this specification illustrate one specific form of the invention, although it is to be understood, that the same may be embodied in other constructions differing in details from that illustrated.

In the drawings:

Figure 1 is a diagrammatic view of an hydraulic system with the present invention applied thereto.

Figure 2 is a vertical section through the control mechanism.

Figure 3 is a horizontal section substantially on the line 3—3 of Figure 2.

Figure 4 is a detail section on the line 4—4 of Figure 3.

Figure 5 is a view of the inner end of the

manually adjustable choke valve hereinafter described.

Figure 6 is a vertical section through the accumulator and the supporting means for the same.

Referring to the drawings in detail, the system illustrated in Figure 1 comprises a main pipe line 10 to which liquid is supplied under pressure from any suitable source such as a pump or series of pumps, the manifold of which is indicated at 11. The numeral 12 indicates a manifold for hydraulic presses, or other mechanism to which the liquid is to be supplied from the line 10. Branched from the line 10 is a secondary pipe line 10^a—10^b, which communicates with the accumulator A through the control mechanism generally designated at M.

The control mechanism includes a valve block 13, which is bored to provide a plurality of ports or passages. To facilitate manufacture these passages are preferably bored from the exterior faces of the block and the outer ends are closed by suitable plugs as hereinafter noted. The passage 14 which is in communication with the pipe 10^a extends longitudinally of the block 13, and at its inner end this passage communicates with a transverse passage 15 in which there is secured an annular bushing or valve seat 16 having at its upper end a beveled face 16^a. A passage 17 communicates with the passage 14 intermediate its length, and an annular bushing or valve seat 18 is secured in this passage. Above and preferably parallel with the passage 14 is a second longitudinal passage 19, the outer end of which is closed by a threaded plug 19^a. Near its outer end the passage 19 communicates with a branch passage 20, the latter being in communication with the pipe 10^b. The passage 19 intermediate its ends intersects or communicates with the passage 17 above mentioned.

At its inner end the passage 19 communicates with a passage 21 in which there is secured an annular bushing or valve seat 22. Passage 21 communicates with a passage 23, which in turn communicates with a passage 24, the latter being in communication with the passage 15 above mentioned. The outer ends of passages 23 and 24 are closed, respectively, by threaded plugs 23^a and 24^a.

A check valve 25 is adapted to cooperate with the seat 18 in the passage 17, this valve

being slidably carried by a plug 26 threaded into the block 13. A spring 27 surrounds the stem of the valve 25 between the head of the valve and the plug 26, this spring 5 serving to normally hold the check valve against the seat 18. This valve 25 therefore is so arranged as to permit free flow of liquid from the passage 14 through the passage 17 toward the accumulator, but 10 it will prevent flow in the opposite direction.

A manually adjustable choke valve 30 is arranged at the point where the passages 19 and 21 intersect. This valve is carried 15 by a plug 31 threaded into the block 13 and provided with internal threads to cooperate with threads on the stem of the valve 30. A suitable packing 32 is interposed between the inner end of the plug 31, and a shoulder 20 on the block 13 to insure water tightness. The inner end of the valve 30 is of conical form and the same may be manually adjusted toward and from the seat 22 by rotating it in the plug 31. This valve may 25 therefore be set to restrict to any desired extent the flow of liquid through the passage 21. To maintain the valve 30 in any desired position of adjustment there is provided a locking block 33 mounted on a stud 34 secured to the block 13, the locking block being fastened to the stud by means of a pin 35 passing through aligned openings in these parts. The locking block 33 carries a pin 33^a which is adapted to enter any one of 30 a number of holes 36 provided in a flange 30^a on the stem of the valve 30. It will thus be seen that after the valve 30 has 35 been adjusted to any desired position and the locking block placed over the stud 34 with the pin 33^a in one of the openings in the flange 30^a of the valve and with the pin 35 in position, the valve will be locked 40 against movement.

At the point where the passages 15 and 24 45 intersect or communicate there is provided a movable choke valve 40, such valve being formed by providing a conical end on a valve plunger 41 which extends to the outside of the block 13, and which is slidably 50 mounted in a plug 42 threaded into said block. A suitable packing 43 is interposed between the inner end of the plug, and a shoulder on the block to insure water tightness. It will be apparent that when the 55 valve 40 is moved inwardly it will cooperate with the seat 16 to restrict flow of liquid from the accumulator through the passages 21, 23, 24 and 15.

An operating plunger 45 extends from the 60 outside of the block 13 into the passage 19 near the outer end of the latter, this plunger being slidably mounted in a plug 46 threaded into the block 13. A suitable packing 65 arranged between the inner end of the plug 46 and a shoulder on the block 13 insures

water-tightness. Preferably the passage 19 is provided with a laterally extending portion 47 to provide space for movement of the plunger 45. The cross sectional area of the plunger 45 is substantially less than 70 that of the plunger 41, the results of which will presently be pointed out.

A lever 50 is pivotally supported on the block 30 as by means of a standard 51, and this lever is provided with a slot 52 at each 75 side of its pivot point and preferably equidistant therefrom. The extended or free end of the lever 50 carries a roller 53 for a purpose hereinafter mentioned. The ends of the plungers 41 and 45 are attached to 80 clevises 54 pivotally connected to trunnion blocks slidably mounted in each of the aforementioned slots formed in the lever 50. It follows that when the lever 50 is oscillated, the plungers 41 and 45 move in opposite directions, one inwardly and the other outwardly relative to the passages in the block 13.

Normally the pressure of the fluid in the 85 various passages of the block 13 is the same throughout, and under such condition the valve plunger 41 is subjected to a greater total pressure than the operating plunger 45 due to its larger cross sectional area, and such plunger 41 is therefore normally retained in its upper or outer position with the conical valve portion 40 removed from its seat 16. In case the pressure adjacent 90 the plunger 41 decreases, the higher pressure exerted upon the plunger 45 will tend to move such plunger outwardly and thus move the valve 40 toward its seat and 95 restrict flow of fluid through the passages 15 and 24.

While the preponderance given to the 100 choke plunger 41 is preferably obtained by the difference in cross sectional area between it and the plunger 45, this preponderance may also be obtained by having two plungers of the same diameter and having the 105 distance from the fulcrum of the lever to the longitudinal axis of the choke plunger substantially greater than the corresponding distance to the other plunger.

Referring to Figure 6, the accumulator A 110 comprises a plunger 60 operating in a cylinder 61 to which the pipe 10^b is connected. Rigidly attached to the plunger 60 is a cross head 62, upon which are supported a series of springs 63. A spring cap 64 is arranged on top of these springs and a series of rods 65 are connected to this cap and extending downwardly through the 115 springs and through openings in the cross head 62. On the lower ends of these rods the accumulator weight or weights 66 are supported. The springs 63 are under a predetermined initial compression which is so 120 adjusted in conjunction with the choke valve 30 that when flow of liquid from the accu- 125

ulator is suddenly discontinued, the kinetic energy of the descending weights 66 is never allowed to attain such magnitude as to completely compress said springs to their solid height. Secured to the weight 66 near the bottom thereof is a lug 67 so arranged as to contact with the roller 53 and operate the lever 60 just before the weight reaches its lowermost position.

- 10 In operation the pumps (not shown) supply fluid under pressure to the manifold 11 from which it is transmitted to the press manifold 12 through the pipe line 10. When fluid is thus being supplied or if more is supplied than demanded, the surplus passes through the branch pipe 10^a, through the passage 14, check valve 25 and passage 19 of the block 13, and then through the pipe 10^b to the accumulator, the weight 66 of 20 which may be raised to its uppermost position. When in this position the accumulator will continue to supply fluid to the manifold 12 even if the pumps are cut off, the fluid at such time flowing through the 25 passages 21, 23, 24 and 15 which passages, in effect, form a by pass around the check valve 25. The choke valve 30 in said by pass is adjusted so that under normal conditions the accumulator will settle at a fairly uniform rate when the pumps are thus cut off. When the presses (not shown) which are supplied from the manifold 12 are stopped, the flow of fluid from the accumulator is discontinued and the plunger 60 is brought 30 to rest, the momentum of the falling weight 66 is gradually reduced by the springs 63 which compress but return to normal when the inertia of the weight is overcome. If during operation any abnormal demand is imposed on the system, for example, on account of putting several presses into operation at once, or on account of a break in the pressure line, then the accumulator weight tends to drop rapidly; the pressure 40 on the side of the choke valve 30 toward the pressure line or presses becomes materially reduced below that on the accumulator side of said valve, such drop in pressure being due to the action of the choke valve 30 in 45 restricting flow of fluid through the conduit or by-pass formed by the passages 21, 23, 24 and 15. At such time, therefore, the pressure on the operating plunger 45 through the lever 50 overbalances that on the valve plunger 41, the choke valve 40 is moved toward its seat 16 which results in stopping or restricting flow of fluid from the accumulator. When the pumps again supply the demand of the presses and build up pressure in the system, the lever 50 and choke valve 40 are returned to their original position. The action of the movable choke valve 40 therefore prevents the accumulator attempting to supply a sudden abnormal demand on the system. Otherwise the de-

scending weight would attain such momentum that extremely high and destructive pressures and objectionable water hammering would be produced in the pipe line when flow of fluid to the presses is discontinued. 70

It will be noted that the conoidal surface forming the choke valve 40 and the complementary surface 16^a on the seat 16, produce an annular passage for fluid which gradually decreases as the valve is closed. This 75 in combination with the resilient connection between the plunger 60 and weight 66 afforded by the springs 63 insures a smooth action and prevents abrupt stoppage which would be detrimental to the successful operation of the automatic choking feature by imposing undue stresses on the choke valve and other parts.

The automatic choking device disclosed in combination with the spring cushioning 80 means for the accumulator weight, is very desirable in an hydraulic system which supplies fluid pressure to a plurality of hydraulic cylinders which operate mill machinery intermittently and at times in unison; the accumulator is in operation almost continuously and is subjected to abrupt changes in its direction of travel; the sudden stop thus occasioned would jar the automatic choking valve and seriously affect its 85 operation but for the resilient connection between the accumulator weight and the plunger. However, it should be understood that while the cushioning means in combination with the choking device is very desirable, it 90 is not absolutely necessary to successful operation of the choking device per se, particularly when the latter is adapted to systems wherein the demand of the press seldom exceeds the normal supply or when the 95 choking device is only embodied as a precaution against a break in the pressure line. 100

Having thus described the invention what is claimed as new and desire to be secured 110 by Letters Patent is:

1. In combination, an accumulator, means for supplying liquid thereto under pressure, a conduit through which liquid may flow from said accumulator, and means controlled by a preponderance of the pressure of the liquid on the inlet side of said conduit over the pressure on the outlet side thereof for restricting flow of the liquid from said accumulator through said conduit. 115

2. In combination, an accumulator, means for supplying liquid thereto under pressure, a conduit through which liquid may flow from said accumulator, a device for restricting flow of liquid from the accumulator, through said conduit, and automatically operated means rendered effective by a preponderance of liquid pressure on the inlet side 120 of said device over the liquid pressure on the 125 said device. 130

outlet side thereof for further restricting flow of liquid from said accumulator through said conduit.

3. In combination, a pipe-line, means for supplying liquid thereto under pressure, an accumulator into which liquid may flow from said line and from which liquid may flow to said line upon drop of pressure in the latter, a conduit through which liquid may flow from said accumulator to said line, a stationary choke device for restricting flow of liquid through said conduit, a movable choke valve on the pipe-line side of said stationary device for further restricting flow of fluid through said conduit, means operated by liquid pressure on the accumulator side of said stationary device for moving said valve toward closed position when said accumulator pressure predominates the line pressure beyond a predetermined degree, and means operated by the pressure of the liquid on the pipe-line side of said stationary device for moving said valve toward open position, when the line pressure is restored from the source of liquid supply.

4. In combination, a pipe-line, means for supplying liquid thereto under pressure, an accumulator into which liquid may flow from said line and from which liquid may flow to said line upon drop of pressure in the latter, a movable choke valve for restricting flow of liquid from said accumulator to said line, and means operated solely by a predetermined preponderance of the accumulator pressure over the line pressure for moving said valve into and out of position to restrict such flow.

5. In combination, a pipe-line, means for supplying liquid thereto under pressure, an accumulator into which liquid may flow from said line and from which liquid may flow to said line upon drop of pressure in the latter, a conduit through which liquid may flow from said accumulator to said line, a movable choke valve for restricting flow of liquid from said accumulator through said conduit, a plunger adapted to be operated by a predetermined preponderance of pressure of liquid on the accumulator side of said valve over the pressure of liquid on the line side thereof, and means for operatively connecting said plunger and said valve.

6. In combination, a pipe-line, means for supplying liquid thereto under pressure, an accumulator into which liquid may flow from said line and from which liquid may flow to said line upon drop of pressure in the latter, a conduit through which liquid may flow from said accumulator to said line, a stationary choke device for restricting flow of liquid through said conduit, a movable plunger subjected to the pressure of liquid on the accumulator side of said device, a second movable plunger subjected

to the pressure of the liquid on the pipe-line side of said device, means operatively connecting said plungers, and means carried by said second named plunger for further restricting flow of fluid through said conduit when said second named plunger is moved by a predetermined preponderance of liquid pressure on the first named plunger over the liquid pressure on the second plunger.

7. In combination, a pipe-line, means for supplying liquid thereto under pressure, an accumulator into which liquid may flow from said line and from which liquid may flow to said line upon drop of pressure in the latter, a conduit through which liquid may flow from said accumulator to said line, a stationary choke device in said conduit, a plunger subjected to the pressure of the liquid on the accumulator side of said device, a second plunger subjected to the liquid pressure on the pipe-line of said device, means for connecting said plungers so as to cause one to move inwardly as the other is moved outwardly relative to said conduit, said second plunger having means for further restricting flow of fluid through said conduit as the same is moved inwardly by a predetermined preponderance of pressure on said first named plunger over the liquid pressure on the second plunger.

8. In combination, a pipe-line, means for supplying liquid thereto under pressure, an accumulator into which liquid may flow from said line and from which liquid may flow to said line upon drop of pressure in the latter, a conduit through which liquid may flow from said accumulator to said line, a stationary choke device in said conduit, a plunger subjected to the pressure of the liquid on the accumulator side of said device, a second plunger subjected to the liquid pressure on the pipe-line side of said device, a lever for connecting said plungers so as to cause one to move inwardly as the other is moved outwardly relative to said conduit, said second plunger having means for further restricting flow of fluid through said conduit as the same is moved inwardly by a predetermined predominance of pressure on said first named plunger, the size of said plungers and their connection to said lever being such as to cause said second plunger to be moved outwardly when the pressure in said pipe line is normal.

9. In combination, a pipe-line, means for supplying liquid thereto under pressure, an accumulator into which liquid may flow from said line and from which liquid may flow to said line upon drop of pressure in the latter, a stationary choke device in said conduit, a plunger subjected to the pressure of the liquid on the accumulator side of said device, a second plunger subjected to the liquid pressure on the pipe-line side of said

- device, a lever to which said plungers are connected at substantially equal distances on opposite sides of the fulcrum thereof, whereby one of said plungers is caused to move inwardly as the other is moved outwardly relative to said conduit, said second plunger having means for further restricting flow of fluid through said conduit as the same is moved inwardly by a predetermined 5 predominance of pressure on said first named plunger, said second plunger being of larger cross sectional area than said first plunger, whereby the same is caused to move outwardly against the pressure of the first 10 plunger when normal pressure exists in said line.
10. In combination, a pipe-line, means for supplying liquid thereto under pressure, an accumulator, a conduit through which 15 liquid may flow from said line toward said conduit, a check valve in said conduit opening toward said accumulator, a by-pass conduit around said check valve, whereby liquid may flow from said accumulator toward said 20 line, and a movable choke valve operated by the pressure of the liquid for restricting flow of fluid from the accumulator through said 25 by-pass conduit upon drop of pressure in said line.
11. In combination, a pipe-line, means for supplying liquid thereto under pressure, an accumulator, a conduit through which liquid may flow upon said line toward said conduit, a check valve in said conduit opening to- 30 ward said accumulator, a by-pass conduit around said check valve, whereby liquid may flow from said accumulator toward said line, a manually operable choke valve in said by- 35 pass conduit for restricting flow of liquid 40 therethrough, a movable choke valve in said by-pass conduit for further restricting the flow of liquid therethrough, and liquid pressure controlled means for operating said last named choke valve.
12. In combination, an accumulator having a plunger and a weight and cushioning means for supporting said weight on said plunger, a pipe-line, a conduit through 45 which liquid may flow from said accumu- 50 lator toward said line, and an automatic choke valve arranged to gradually restrict flow of fluid from the accumulator toward said line, when the accumulator pressure predominates the line pressure beyond a pre- 55 determined degree.
13. In combination, an accumulator having a plunger and a weight, cushioning means comprising a series of coiled springs for supporting said weight on said plunger, 60 a pipe-line, a conduit through which liquid may flow from the accumulator toward said

line, a choke valve for restricting flow of liquid through said conduit, means operated by the pressure of the liquid for moving said choke valve to gradually restrict flow of liquid through said conduit, when the accumulator pressure predominates the line pressure beyond a predetermined degree. 65

14. In combination, a pipe-line, an hydraulic accumulator associated therewith, a conduit through which liquid may flow from said accumulator toward said line, a choke valve in said conduit for restricting flow of liquid therethrough, and means operated by the downward movement of a part of the accumulator for closing said valve, said means being responsive to a predetermined pressure in the pipe line to restore it to its normal position when said part of the accumulator has been raised. 70 75

15. In combination, a pipe-line, an hydraulic accumulator associated therewith and having a weight, a conduit through which liquid may flow from said accumulator toward said line, a choke valve in said conduit, and means operated by the descent of said accumulator weight for closing said valve, said means being responsive to a predetermined pressure in the pipe line to restore it to its normal position when the accumulator weight has been raised. 80 85 90

16. Control mechanism for an hydraulic accumulator, comprising a block having a passage through which liquid may flow toward the accumulator, a check valve in said passage opening toward the accumulator, a by-pass conduit in said block around said check valve and through which liquid may flow from the accumulator, and an automatically operated choke valve for restricting flow of liquid through said by-pass conduit. 95 100

17. Control mechanism for an hydraulic accumulator system, comprising a conduit through which liquid may flow from the accumulator to a pipe line, a choke valve in said conduit, a balanced pressure device for closing said valve, said device rendered effective only when the pipe line pressure has dropped below a predetermined minimum. 105 110

18. Control mechanism for an hydraulic accumulator system, comprising means for restricting flow of liquid from the accumulator, and means subject to a predominance of liquid pressure on the inlet side of said flow restricting means, for operating the latter. 115

In testimony whereof I hereunto affix my 120 signature.

HOWARD H. HUMMEL.
